(57) **CLAIM**

The ornamental design for a bar stool, as shown and described.

DESCRIPTION

FIG. 1 is a front, left side perspective view of a bar stool showing my new design;

FIG. 2 is a front perspective view thereof;

FIG. 3 is a rear perspective view thereof;

FIG. 4 is a right side perspective view thereof;

FIG. 5 is a left side perspective view thereof;

FIG. 6 is a top perspective view thereof;

FIG. 7 is an enlarged fragmentary rear perspective view showing the seat thereof;

FIG. 8 is an enlarged fragmentary rear perspective view showing the backrest thereof; and,

FIG. 9 is an enlarged fragmentary front perspective view showing the backrest thereof.

The broken lines illustrate portions of the bar stool that form no part of the claimed design.
